US0D1108582S

(12) **United States Design Patent** (10) **Patent No.:** **US D1,108,582 S**
(45) **Date of Patent:** **** Jan. 6, 2026**

(54) **IRRIGATION SPIKE**

(71) Applicant: **DripScrew, Inc.**, Porterville, CA (US)

(72) Inventor: **Jonathan David Ross**, Lindsay, CA (US)

(**) Term: **15 Years**

(21) Appl. No.: **29/968,943**

(22) Filed: **Oct. 18, 2024**

Related U.S. Application Data

(63) Continuation of application No. 29/855,563, filed on Oct. 4, 2022.

(51) **LOC (15) Cl.** **23-01**

(52) **U.S. Cl.**

USPC **D23/213**

(58) **Field of Classification Search**

(57) **CLAIM**

The ornamental design for an irrigation spike as shown and described.

DESCRIPTION

FIG. 1 is a perspective view of an irrigation spike showing my new design;

FIG. 2 is a perspective view of the irrigation spike of FIG. 1;

FIG. 3 is an elevation posterior view of the irrigation spike of FIG. 1;

FIG. 4 is an elevation anterior view of the irrigation spike of FIG. 1;

FIG. 5 is a first side elevation view of the irrigation spike of FIG. 1;

FIG. 6 is a second side elevation view of the irrigation spike of FIG. 1;

FIG. 7 is a bottom plan view of the irrigation spike of FIG. 1; and,

FIG. 8 is a top plan view of the irrigation spike of FIG. 1. The broken lines shown in FIGS. 1-8 are for the purpose of illustrating portions of the irrigation spike that form no part of the claimed design.

1 Claim, 7 Drawing Sheets
